CLAIM

The ornamental design for a holiday bird treat, as shown and described.

DESCRIPTION

FIG. 1 is a perspective view of the holiday bird treat showing the new design;

FIG. 2 is a top view of the holiday bird treat showing the new design;

FIG. 3 is a front view of the holiday bird treat showing the new design;

FIG. 4 is a side view of the holiday bird treat showing the new design; the opposite side being a mirror image;

FIG. 5 is a back view of the holiday bird treat showing the new design; and,

FIG. 6 is a bottom view of the holiday bird treat showing the new design.

The textured surface partially shown is understood to be continuous over all surfaces except as indicated.
